[57] CLAIM

The ornamental design for a speaker mounting apparatus, as shown and described.

DESCRIPTION

FIG. 1 is a perspective view of a first embodiment of a speaker mounting apparatus showing my new design; the broken line showing of the speaker is for illustrative purposes only and forms no part of the claimed design.

FIG. 2 is a side elevation of the mounting apparatus of FIG. 1, the opposite side being a mirror image thereof.

FIG. 3 is a plan view of the mounting apparatus as viewed from the top in FIG. 2.

FIG. 4 is a bottom plan view of the mounting apparatus as viewed from the bottom in FIG. 2.

FIG. 5 is a vertical elevation of the mounting apparatus as viewed from the right in FIG. 2.

FIG. 6 is a vertical elevation of the mounting apparatus as viewed from the left in FIG. 2.

FIG. 7 is a vertical elevation of a second embodiment of the speaker mounting apparatus, the mounting apparatus utilizing the same, identical parts shown in FIGS. 1-6 but with the rod member in inverted condition on the mount member.

FIG. 8 is a vertical elevation of a third embodiment of the speaker mounting apparatus, the mounting apparatus having the same, identical parts as in FIGS. 1-7 but the members shown in yet another interengaging orientation relative to each other; and,

FIG. 9 is a vertical elevation of a fourth embodiment of the speaker mounting apparatus, the mounting apparatus having the same, identical parts as FIGS. 1-8 but showing the members in yet another interengaging relation relative to each other.
